HAND LIFT TRUCK

George Quayle, Philadelphia, Pa., assignor to The
Yale & Towne Manufacturing Company, Stamford,
Conn., a corporation of Connecticut

Application March 18, 1936, Serial No. 69,478

26 Claims. (Cl. 214—65)

This invention relates to a hand lift truck of the type in which a load lifting frame is elevated by the operation of lifting mechanism, which lifting mechanism is usually operated in turn by 5 a lifting and steering lever.

More particularly, my invention relates to a truck of the type described in which a relatively heavy and compact load is adapted to be elevated by the truck, the load being mounted on pallets 10 and therefore requiring a low extending type of overhanging fork load frame for its handling. My truck is especially adapted for handling relatively heavy sheets of tin plate stored on pallets, and for this purpose I use forks movable into a 15 very low position and adapted to be elevated to a position wherein the load may be transported. It will be readily appreciated that the placing of a relatively heavy compact load on overhanging forks upsets the normal balance of a truck 20 of the class described, so that it will tip readily when accepting the load and will be incapable of transporting the load, even should it be possible to actually lift the load. My invention relates especially to means for facilitating the lifting of 25 a relatively heavy load on overhanging forks mounted on a relatively light hand lift truck, and to means for thereafter facilitating the moving of the load on the truck.

Before describing in detail my truck, it may be 30 well to indicate generally the basic operating principles thereof, and to indicate generally the characteristics of the features whereby it is made to operate efficiently.

Preferably, my truck comprises a main frame 35 having at its front end a lifting mechanism which may be of any type well known in the art, but which I prefer to be of the type shown in the Stuebing patent, No. 1,785,368. This lifting mechanism is connected to a lifting frame, which in 40 this case, is preferably a pair of forks which are to be lifted relatively to the main frame, but which need not actually be even connected to the main frame. A presser foot is adapted for co-operation with the lifting frame, or the forks, as 45 the case may be, and is so mounted relatively to the forks that by operation of the lifting mechanism when the forks are loaded, the presser foot will be separated from the lifting forks and will move against the ground and thereafter accept 50 the entire load imposed on the forks.

Preferably, this is accomplished by having the 55 presser foot pivotally supported on the main frame and maintained by springs in an upper position, so as not to interfere with the movement of the truck. The lifting forks are preferably

supported relatively to the main frame by the presser foot, so that any load imposed on the forks will immediately move the presser foot into a downward position against the ground. The lifting mechanism at the front end of the truck 5 is interconnected to the presser foot and lifting forks so that it tends to separate the two on operation of the lifting mechanism. This, of course, acts to elevate the forks and the load.

As a further feature of my invention, the forward load supporting wheels of the truck are mounted for lateral movement relatively to the truck once the lifting forks have been elevated and the load assumed by the presser foot. As a further feature, the main frame itself is actually 10 elevated relatively to the presser foot so as to relieve the forward wheels of the load. Then, the operator need only move the wheels laterally into a position directly under the elevating forks, which will of course still be supported by the 15 presser foot. If now the lifting mechanism be released as described in the Stuebing patent, the lifting forks will come down into a lower position against supporting means associated with the load wheels, thus relieving the presser foot of the load. 20 Thereafter, the springs which maintain the presser foot in an upper position will be free to move the presser foot into the said upper position, and the truck may then be moved freely.

There are, of course, further features of the 30 invention which I shall describe in more detail hereinafter. I believe my invention to be of a very basic nature, and I do not wish to be limited to any particular modification, but rather believe myself entitled to broad claims and a broad interpretation of those claims.

For a detailed description of my invention, I shall now refer to the drawings wherein Fig. 1 is a partial section along lines 1—1 of Fig. 4. Fig. 2 is a view of the forward portion of the truck 40 shown in Fig. 1, with the lifting forks in an elevated position and with the load being supported by the presser foot. Fig. 3 is a view of that portion of the truck shown in Fig. 2 with the load wheels moved to a position under the lifting forks, 45 and with the lifting forks supported thereby for movement. Fig. 4 is a top view of the parts of Fig. 1 with the check eliminated for purposes of clarity. Fig. 5 is a view taken along lines 5—5 of Fig. 1. Figs. 6, 7 and 8 are perspective views 50 of the presser foot, the lifting forks and the movable load wheels, respectively.

Referring now more particularly to the drawings, the truck has a main frame 10 having a lifting head 11 equipped with a steering and lift- 55

ing handle 12 and steering wheels 13, all of which operate as described in the Stuebing patent supra. In Fig. 5, I show some of the mechanism of the steering head 11, the main portion of this mechanism being the lifting ratchet wheel 14, which is operated by pumping movement of the handle 12 and actuates the lifting mechanism through a pair of crank arms 15. Since this mechanism is old in the art and does not form a part of my invention, I shall naturally not go into further detail in describing it. Suffice it to say that this type of lifting mechanism, or any type well known in the art, may quite well cooperate with the features of my invention in a sufficiently effective manner to give the results required.

A presser foot designated generally by reference numeral 16, has a pair of presser feet 17 and a vertical portion 18. Ears 19 on the vertical portion 18 are connected through means of upper links 20 with the main frame, these links being pivotally connected to the main frame by a rod 21. Ears 22 are similarly formed at the lower portion of the member 18 of the presser foot, and links 23 pivoted to the main frame at 24 connect the ears 22 to the main frame. The presser foot has a further pair of ears 25 carrying a horizontal member 26, drilled at 27 for cooperation with springs 28. These springs are suspended from an L-shaped member 29 on the main frame, and thus resiliently support the presser foot relatively to the main frame in its position illustrated in Fig. 1.

The lifting frame is preferably in the form of forks 30, having vertical portions 31 connected by a horizontal bracing member 32, and a further bracing member 33. Lower ears 34 are secured to the vertical portions 31 and these ears are connected to the main frame 10 through means of links 35, which links are pivoted to the main frame on the axis 24, or the same axis on which the links 23 of the presser foot are pivoted. Similarly, the vertical portions 31 have upper ears 36 carrying links 37 pivoted to the main frame through shaft 21, which is the same shaft that supports the link 20 of the presser foot.

While, of course, I have shown the lifting forks pivoted to the main frame on the same axis as the presser foot, it should be understood that it may be pivoted on other axes or otherwise supported relatively to the presser foot itself. While the basic relationship of the presser foot and forks should preferably be that herein described, this basic relationship may take any number of different forms.

A check member 38 of the fluid type well known in this art is connected to the upper horizontal bracing member 33 of the forks at 38a, and at its lower end to the bracket 39 fixed on the member 18 of the presser foot, as is shown in Fig. 5. This check acts to slow down the movement between the lifting forks and the presser foot, as will be readily understood by those skilled in the art.

Each of the ears 25 of the presser foot is drilled out as at 40 for the support of the shaft 41, at each end of which is mounted an arm 42 connected by pivot 43 with a pair of link members 44, best illustrated in Fig. 5. Each pair of link members 44 is in turn pivoted at 45 to each of the bell crank arms 15 of the lifting mechanism, including the ratchet 14 maintained in lifting head 11. Each of the bell crank levers 42 is connected, through a pivot 46, with a link 47 pivoted at 48 to one of the lower ears 34 of the lifting forks 30.

It will readily be appreciated by viewing Figs. 1 and 2 that when the bell crank arms 15 are rotated clockwise by operation of the lifting handle 12, the bell crank 42 will be rotated clockwise through its connection with the links 44, thus lifting the forks 30 relatively to the presser foot 16 by, in effect, separating the presser foot and the lifting forks in a manner well shown in Fig. 2. In effect, the toggle including pivot 40 on the presser foot and pivot 48 of the lifting forks, and members 42 and 21, is straightened for obtaining the movement just described. Should there be no load on the lifting forks 30, this movement of the lifting forks relatively to the presser foot may be mere relative movement without the presser foot actually coming in contact with the ground. However, if there is a load, such as "A" of Fig. 2, on the lifting forks 30, then that load will be accepted by the presser foot 16 which will move with its presser feet 17 into a position 20 against the ground and against the resilient force of springs 28. This movement will occur immediately upon the application of load "A" to the forks 30. Thereafter, operation of the lifting mechanism will tend to separate the lifting forks 25 from the presser foot more and more until the load is fully elevated, as shown in Fig. 2.

The main frame 10 of the truck is equipped with lugs 49 cooperable with lugs 50 on the lifting forks so that when the lifting forks reach the position of Fig. 2, the main frame 10 is elevated by the forks relatively to the presser feet 17. This moves the frame from a position wherein it rests on supporting portions 50 carried by frame members 51, which in turn carry the load wheels 52, through means of the axle 53. The frame members 51 of the load wheels 52 are movable laterally from the position illustrated in Fig. 1 to the position illustrated in Fig. 3, through means of a lever 54 pivoted to the frame members 40 51 at 55, and pivoted at 56 to the main frame 10, and having a relatively long extending portion 57 whereby the moving leverage may be obtained.

With the load elevated as in Fig. 2, and with the main frame no longer resting on the upper surfaces of the members 50, the frame members 51 may be moved from the position of Fig. 2 to the position of Fig. 3 with very little effort on the part of the operator, by merely rotating the lever 57 about its pivot 56, and in a clockwise direction, looking at Fig. 1. This movement is controlled partly by a balancing spring 54a which tends to maintain the lever 54, 57 in one of its extreme positions. Thereafter, if the lifting mechanism in the lifting head 11 is released in a manner well known in the art, and best described in the Stuebing patent previously referred to, the forks 30 will tend to descend, checked of course by the member 38 until they rest on the member 50 supported by the frame 51 and load wheels 52, as is well illustrated in Fig. 3. As soon as the members 50 accept the load of the forks 30, the springs 28 will no longer be stressed by the load and they will act to pull the presser feet 16 upwardly so as to remove the presser feet 17 from the ground.

The presser feet 17 have lug portions 58 and 59. The lugs 58 cooperate with the axle 53 in the position of the parts illustrated in Fig. 1 and maintain it relatively rigid. Similarly, in Fig. 3 the lugs 59 cooperate with the axle 53 for maintaining it relatively rigid.

I believe that the operation of my truck will

now be relatively clear to those skilled in the art, but it may be well to go through one complete operation in order to even better clarify its action.

5 In the initial position of the truck, the forks 30 constituting the lifting platform are in the position of Fig. 1, and the main frame is supported on members 50, while the axle 53 is held in position by cooperation with the lugs 58 on the presser feet 17, the presser foot being maintained in an upper position with the feet off the ground through means of springs 28. Operation of the lifting handle 12 serves to rotate the crank arms 15 which in turn pull on the links 44 and 10 rotate the bell cranks 42 for moving the lifting forks relatively to the presser foot. If there is a 15 load on the forks sufficient to overcome the springs 28, that load will naturally be transferred to the presser foot, which will move 20 through its links 20 and 23 relatively to the main frame into the position of Fig. 2 with the feet 17 against the ground. Thereafter, further operation of the lifting handle 12 will elevate the 25 forks to the position of Fig. 2 and will at the same time, through the coaction of lugs 49 and 30 50, move the main frame 10 off its support on the members 50. At this point, the portions of check 38 will reach a fully outstretched position 35 ready to absorb the movement of the load downwardly with the lifting forks when the elevating mechanism in the head 11 is released.

If it is desired to move the load "A" of Fig. 2, it is merely necessary to apply effort to the extension 57 of the member 54 and rotate that 35 member against the force of spring 54a from the position of Fig. 1 to the position of Fig. 2, wherein the wheels 52 will be positioned under the load forks 30. If the lifting mechanism in the head 40 11 is then released, the forks will descend slowly under the control of the check 38 until they rest on the members 50. Thereafter, the load being taken off the presser foot 16, the presser foot 45 will rise under the influence of springs 28 until its lugs 59 abut the axle 53 for holding the axle 50 in position. Incidentally, in this position of the parts, the spring 54a will act also to hold the lever 57 and therefore the wheel assembly in its proper operating position.

I now claim:

50 1. In a lift truck of the class described, a main frame, a load lifting frame, elevating means on said main frame, toggle means, in effect, operated by said elevating means for elevating said load lifting frame relatively to said main frame, and means movable against the ground and into truck stabilizing position actuatable incidental to the elevating of said load lifting frame.

2. In a lift truck of the class described, a main 60 frame, a forwardly extending load lifting frame supported by said main frame, means for elevating said load lifting frame relatively to said main frame, presser means movable against the ground incidental to the elevating of a load and said 65 load lifting frame by said elevating means whereby to prevent tipping of said truck, a longitudinally movable wheeled frame normally under said main frame, means whereby said wheeled frame is moved to a position under said lifting frame when said frame is elevated, whereby said 70 wheeled frame supports said lifting frame when said lifting frame is lowered thereafter.

3. In a lift truck of the class described, a main 75 frame, a wheeled supporting frame for said main frame normally under said main frame, a for-

wardly extending load lifting frame, means mounting said lifting frame for movement relatively to said main frame, means for elevating said load lifting frame relatively to said main frame, a presser foot for said lifting frame, means 5 whereby the said presser foot assumes a load imposed on said lifting frame and moves against the ground in supporting relation to said lifting frame when a load is applied to said lifting frame and lifted, said wheeled supporting frame being 10 thus relieved of the weight of said main and load lifting frames, and means whereby said wheeled frame is moved under said load lifting frame whereby to support said lifting frame independently of said presser foot when said lifting frame 15 is lowered thereafter.

4. In a lift truck of the class described, a main frame, a load lifting frame, means for elevating said load lifting frame relatively to said main frame, means mounting said lifting frame for lifting movement relatively to said main frame, a presser foot for said lifting frame, means whereby said presser foot assumes a load imposed on said lifting frame and moves against the 20 ground in supporting relation to said lifting frame whereby to support a load on said lifting frame, and means operable by said elevating means for thereafter elevating said lifting frame 25 relatively to said presser foot.

5. In a lift truck of the class described, a main frame, a load lifting frame, lifting means for elevating said load lifting frame, means mounting said lifting frame for lifting movement relatively to said main frame, a presser foot for said lifting frame, means whereby said presser foot assumes a load imposed on said lifting frame and moves against the ground in supporting relation to said lifting frame, means whereby said lifting means 30 separate said load lifting frame from said presser foot whereby to lift said lifting frame, and wheels carried by said main frame movable under said lifting frame when said frame is elevated, whereby to assume the load and relieve said presser foot 35 therefrom.

6. In a lift truck of the class described, a main frame, a load lifting frame, lifting means on said main frame for elevating said load lifting frame, a presser foot for assuming substantially the load and the weight of said load lifting frame when the said frame is elevated by said lifting means, means whereby said presser foot is maintained spaced from the ground when said lifting frame is not in load assuming position, and means whereby said presser foot moves against the 40 ground upon the assumption of a load by said lifting frame.

7. In a lift truck of the class described, a relatively short main frame, wheels supporting said frame, lifting forks pivoted to said main frame at its forward end, a presser foot also pivoted to said main frame at its forward end, lifting means carried by said main frame and so connected to said presser foot and said lifting forks as to separate said presser foot and lifting forks when operated, for lifting said forks through said presser foot, a 65 spring, means whereby said spring holds said lifting forks and said presser foot in an elevated position until a load is applied to said forks whereupon said presser foot is forced against the ground and thereafter supports the load lifting 70 forks as said forks are separated from said presser foot by actuation of said lifting means.

8. In a lift truck of the class described, a main frame, wheels supporting said frame, a presser foot pivoted relatively to said main frame at its 75

forward end, a load lifting frame adapted to be elevated relatively to said presser foot and said main frame, lifting means so connected to said presser foot and load lifting frame as to separate them when operated and thus elevate the load lifting frame through said presser foot, whereby when a load is applied to said lifting frame and said lifting means are actuated, said presser foot is forced against the ground and thereafter supports the load lifting frame as said frame is separated from said presser foot.

9. In a lift truck of the class described, a main frame, wheels supporting said frame, a presser foot pivoted relatively to said main frame at its forward end, a load lifting frame supported by and adapted to be elevated relatively to said presser foot and said main frame, lifting means so connected to said presser foot and load lifting frame as to separate them when operated and thus elevate the load lifting frame through said presser foot, whereby when a load is applied to said lifting frame and said lifting means are actuated said presser foot is forced against the ground and thereafter supports the load lifting frame as said frame is separated from said presser foot, and a spring for maintaining said load lifting frame and presser foot in an elevated position until a load is applied to said frame sufficient to force the presser foot against the ground in opposition to said spring.

10. In a lift truck of the class described, a main frame, wheels supporting said frame, a presser foot pivoted relatively to said main frame at its forward end, a load lifting frame adapted to be elevated relatively to said presser foot and said main frame, lifting means carried by said main frame and so connected to said presser foot and load lifting frame as to separate them when operated and thus elevate the load lifting frame through said presser foot, whereby when a load is applied to said lifting frame and said lifting means are actuated said presser foot is forced against the ground and thereafter supports the load lifting frame as said frame is separated from said presser foot, supporting wheels normally mounted under the main frame of said truck, means for moving said wheels under the load lifting frame when said frame is elevated to a predetermined position relatively to the presser foot then maintained against the ground, and means movable with said wheels and on which said lifting frame may then be lowered to apply the load to said wheels and remove it from said presser foot.

11. In a lift truck of the class described, a relatively short main frame, wheels supporting said frame, a presser foot pivoted relatively to said main frame at its forward end, a load lifting frame adapted to be elevated relatively to said presser foot and said main frame, lifting means carried by said main frame and so connected to said presser foot and load lifting frame as to separate them when operated and elevate the load lifting frame through said presser foot, whereby when a load is applied to said lifting frame and said lifting means are actuated, said presser foot is forced against the ground and thereafter supports the load lifting frame as said frame is separated from said presser foot, a spring for maintaining said load lifting frame and presser foot in an elevated position until a load is applied to said lifting frame sufficient to force the presser foot against the ground in opposition to said spring, supporting wheels normally mounted under the short main frame of said truck, means

for moving said wheels under the load lifting frame when said frame is elevated to a predetermined position relatively to said presser foot then maintained against the ground, and means movable with said wheels and on which said load lifting frame may then be lowered to apply the load to said wheels and remove it from said presser foot so that said presser foot is lifted off the ground by said spring means to permit the truck to be moved to transport the load.

12. In a lift truck of the class described, a relatively short main frame, lifting forks pivoted to said main frame at its forward end, a presser foot also pivoted to said main frame at its forward end, lifting means carried by said main frame and so connected to said presser foot and said lifting forks as to separate them when operated and thus lift the said forks through said presser foot, a spring, means whereby said spring holds said lifting forks and said presser foot in an elevated position until a load is applied to said forks whereby said presser foot is forced against the ground and thereafter supports the load lifting forks as said forks are separated from said presser foot by actuation of said lifting means, supporting wheels normally mounted under the short main frame of said truck, means for moving said wheels under the load lifting forks when said forks are elevated to a predetermined position relatively to the presser foot then maintained against the ground, and means movable with said wheels and on which said lifting forks may then be lowered to apply the load to said wheels and remove it from said presser foot so that said presser foot is lifted off the ground by said spring means to permit the truck to be moved to transport the load.

13. In a lift truck of the class described, a relatively short main frame, a presser foot pivoted to said main frame at its forward end, a load lifting frame adapted to be elevated relatively to said presser foot and said main frame, lifting means carried by said main frame and so connected to said presser foot and load lifting frame as to separate them when operated and elevate the load lifting frame through said presser foot, whereby when a load is applied to said lifting frame and said lifting means are actuated said presser foot is forced against the ground and thereafter supports the load lifting frame as said frame is separated from said presser foot, supporting wheels normally mounted under the short main frame of said truck, means for moving said wheels under the load lifting frame when said frame is elevated to a predetermined position relatively to the presser foot then maintained against the ground, means movable with said wheels on which said load lifting frame may then be lowered to apply the load to said wheels and remove it from said presser foot, and means on said presser foot for stabilizing said wheels.

14. In a lift truck of the class described, a relatively short main frame, wheels supporting said frame at its rear end, wheels supporting said frame at its forward end, a presser foot pivoted to said main frame at its forward end, a load lifting frame adapted to be elevated relatively to said presser foot and said main frame, lifting means carried by said main frame and so connected to said presser foot and load lifting frame as to separate them when operated and thus elevate the load lifting frame through said presser foot, whereby when a load is applied to said lifting frame and said lifting means are actuated said presser foot is forced against the ground and

- thereafter supports the load lifting frame as said lifting frame is separated from said presser foot, means whereby continuous operation of said lifting means lifts the main frame also relatively to said presser foot so as to relieve the wheels at the forward end of any load, means for moving said wheels at the forward end under the load lifting forks when said forks and said main frame are elevated to a predetermined position relatively to the presser foot then maintained against the ground, and means movable with said wheels and on which said load lifting frame may then be lowered to apply the load to said wheels and remove it from said presser foot.
15. In a lift truck of the class described, a relatively short main frame, wheels supporting said frame at its rear end, wheels supporting said frame at its forward end, a presser foot pivoted to said main frame at its forward end, a load lifting frame adapted to be elevated relatively to said presser foot and said main frame, lifting means carried by said main frame and so connected to said presser foot and load lifting frame as to separate them when operated and elevate the load lifting frame through said presser foot, whereby when a load is applied to said lifting frame and said lifting means are actuated said presser foot is forced against the ground and thereafter supports the load lifting frame as said lifting frame is separated from said presser foot, means whereby continuous operation of said lifting means lifts the main frame also relatively to said presser foot so as to relieve the wheels at the forward end of any load, a spring for maintaining said load lifting frame and presser foot in an elevated position until a load is applied to said frame sufficient to force the presser foot against the ground in opposition to said spring, means for moving said wheels at the forward end under the load lifting forks when said forks and said main frame are elevated to a predetermined position relatively to the presser foot then maintained against the ground, means movable with said wheels and on which said load lifting frame may then be lowered to apply the load to said wheels and remove it from said presser foot so that said presser foot is lifted off the ground by said spring means to permit the truck to be moved to transport the load.
50. In a lift truck of the class described, a main frame, rear supporting wheels on said main frame, forward supporting wheels for said frame movable laterally relatively thereto, said frame resting normally on means supported by said wheels, means for lifting the main frame so as to relieve the forward supporting wheels of the weight thereof, and means for then moving said wheels laterally relatively to said main frame to change the truck wheel base.
60. In a lift truck of the class described, a main frame, a load lifting frame, lifting means for elevating said load lifting frame, a presser foot for said load lifting frame, means whereby the lifting means separates said presser foot from said load lifting frame and forces said foot against the ground to support said load lifting frame for elevating movement by said lifting means, supporting wheels for the main frame of said truck relieved of the load of said main and lifting frames by the action of said presser foot, and means for moving said wheels to a point under said load lifting frame when said load lifting frame is elevated relatively to said presser foot.
65. In a lift truck of the class described, a main frame, a load lifting frame, lifting means on said main frame for elevating said load lifting frame, a presser foot for said load lifting frame, means whereby the lifting means separates said presser foot from said load lifting frame and forces said foot against the ground to support said load lifting frame for elevating movement by said lifting means, supporting wheels for the main frame of said truck, means for moving said wheels to a point under the load lifting frame when said load lifting frame is elevated relatively to said presser foot, and means supported by said moving wheels for taking the load of said lifting frame when said frame is lowered from an elevated position relatively to said presser foot.
70. In a lift truck of the class described, a main frame, a load lifting frame, lifting means on said main frame for elevating said load lifting frame, a presser foot for said load lifting frame, means whereby the lifting means separates said presser foot from said load lifting frame and forces said foot against the ground to support said load lifting frame for elevating movement by said lifting means, and a fluid check between said presser foot and load lifting frame for absorbing the downward movement of said load lifting frame.
75. In a lift truck of the class described, a main frame, a presser foot and load lifting frame supported through said main frame, lifting mechanism of the type operated by a lifting lever carried by said main frame, means whereby said lifting mechanism is inter-connected between said presser foot and said load lifting frame for lifting said load lifting frame by separating it from said presser foot while said presser foot is maintained against the ground.
80. In a lift truck of the class described, a main frame, a presser foot and load lifting frame supported through said main frame, a spring for maintaining said load lifting frame and presser foot in a predetermined position with the presser foot off the ground, said presser foot being movable against the ground in opposition to said spring when a load is applied to said load lifting frame, lifting mechanism of the type operated by a lifting lever carried by said main frame, means whereby said lifting mechanism is inter-connected between said presser foot and said load lifting frame for lifting said load lifting frame by separating it from said presser foot while said presser foot is maintained against the ground.
85. In a lift truck of the class described, a main frame, rear supporting wheels for said main frame, forward supporting wheels for said main frame mounted for longitudinal movement relatively to said main frame when said wheels are relieved of the load of said main frame whereby to change the wheel base of the truck, and lifting means for so relieving the said forward supporting wheels of the weight of said main frame.
90. In a lift truck of the class described, a main frame, rear supporting wheels for said main frame, forward supporting wheels for said main frame mounted for longitudinal movement relatively to said main frame when said wheels are relieved of the load of said main frame whereby to change the wheel base of the truck, a lifting frame overhanging the forward end of the truck, and means for lifting said lifting frame together with said main frame relatively to said forward supporting wheels whereby to so relieve the said wheels of the weight of said main frame.
95. In a lift truck of the class described, a main

frame, rear supporting wheels for said main frame, forward supporting wheels for said main frame mounted for longitudinal movement relatively to said main frame when said wheels are relieved of the load of said main frame whereby to change the wheel base of the truck, a lifting frame overhanging the forward end of the truck, means for lifting said lifting frame together with said main frame relatively to said forward supporting wheels whereby to so relieve the said wheels of the weight of said main frame, and means for moving said wheels longitudinally thereafter under the said overhanging lifting frame to support the said lifting frame when it is lowered by said lifting means.

25. In a lift truck of the class described, a main frame, rear supporting wheels for said main frame, forward supporting wheels for said main frame mounted for longitudinal movement relatively to said main frame when said wheels are relieved of the load of said main frame whereby to change the wheel base of the truck, and lift-

ing means engaging the ground for so relieving the said forward supporting wheels of the weight of said main frame.

26. In a lift truck of the class described, a main frame, rear supporting wheels for said main frame, forward supporting wheels for said main frame mounted for longitudinal movement relatively to said main frame when said wheels are relieved of the load of said main frame whereby to change the wheel base of the truck, a lifting frame overhanging the forward end of the truck, means engaging the ground for lifting said lifting frame together with said main frame relatively to said forward supporting wheels whereby to so relieve the said wheels of the weight of said main frame, and means for moving said wheels longitudinally thereafter under the said overhanging lifting frame to support the said lifting frame when it is lowered by said lifting means.

20 GEORGE QUAYLE.
